US00D847793S

(12) **United States Design Patent** (10) **Patent No.:** **US D847,793 S**
Wendling et al. (45) **Date of Patent:** **** May 7, 2019**

(54) **REMOTE CONTROL**

(71) Applicant: **Crestron Electronics, Inc.**, Rockleigh, NJ (US)

(72) Inventors: **Byron Wendling**, Nyack, NY (US); **Wayne Owens**, Pearl River, NY (US); **André Poulheim**, Frechen (DE)

(73) Assignee: **Crestron Electronics, Inc.**, Rockleigh, NJ (US)

(**) Term: **15 Years**

(21) Appl. No.: **29/617,502**

(22) Filed: **Sep. 14, 2017**

(51) **LOC (11) Cl.** **14-03**

(52) **U.S. Cl.** USPC **D14/218**

(58) **Field of Classification Search**

USPC D14/218; D13/168
CPC G07C 9/00103; G06F 3/0489
